UNITED STATES PATENT OFFICE.

GEORGE P. DIKE, OF BROOKLINE, MASSACHUSETTS.

FOOTWEAR.

Application filed January 20, 1923. Serial No. 613,801.

This invention relates to footwear and especially, although not exclusively, to overshoes of the type known as arctics.

The invention has for its object the provision of an overshoe or other foot covering having an upper adapted to be held sufficiently closely about the ankle and leg of the wearer to present a neat and trim appearance and to exclude snow, dirt and moisture, but in which the usual troublesome clasps for securing the upper in place are eliminated, enabling the shoe to be put on or taken off as readily as a so-called Russian boot having a loose leg and ankle portion.

The foregoing and other objects of the invention, together with means whereby the same may be carried into effect, will best be understood from the following description of certain forms or embodiments theretofore illustrated in the accompanying drawings. It will be understood, however, that the particular constructions described and shown have been chosen for illustrative purposes merely and that the invention, as defined by the claims hereunto appended, may be otherwise practised without departure from its spirit and scope.

In said drawings—

Fig. 1 is a side elevation of a high overshoe or arctic constructed in accordance with the invention.

Fig. 2 is a front elevation of a slightly modified construction, the upper being closed or in the position assumed thereby when the overshoe is being worn.

Fig. 3 is a perspective view of the upper portion of the overshoe shown in Fig. 2, the upper being opened in order to permit the overshoe to be put on or taken off.

Fig. 4 is a plan view of the top of the overshoe with the upper closed.

Fig. 5 is a detail view of the clasp used in connection with the overshoes above referred to.

Figs. 6 and 7 are detail views of the spring hinge forming part of the clasp.

Figs. 8, 9 and 10 are views corresponding substantially to Figs. 2, 3 and 4, respectively, illustrating another form of the invention.

The invention is herein shown as embodied in an overshoe or arctic whose sole 12, counter 13 and foxing 14 may be of any usual construction, as may also the rear portion of the upper 15. The forward por-

tions *b* and *c* of the upper are permanently connected at their edges to a strip or section *a* performing the function of the usual bellows tongue, thereby providing an upper which is circumferentially closed, but which, in use, is folded in opposite directions along lines *d* and *e* at the connected edges of the tongue *a* and portions *b* and *c* of the upper proper. The arrangement is such that the upper may be opened to its fullest extent, as shown in Fig. 3, to permit the overshoe to be put on or taken off, but when said overshoe has been put on, the portion *b* of the upper is drawn about the leg and folded inwardly along the line *d* under the portion *a*, and the portion *c* then folded outwardly thereover along the line *e* in the form of a two-ply triangular flap *A* with the base of the triangle uppermost, so as to assume the position shown in Figs. 1 and 4. The upper is preferably so cut that the fold *e* is in a substantially straight diagonal line which extends from the inner side of the foot at a point *f* adjacent the bottom of the overshoe to a point *g* at the outer side of the leg adjacent the top of the overshoe. This arrangement permits the several plies or layers of the folded upper to lie flat one upon the other, the folding of the upper on the diagonal line *e* causing the closure of the upper at the top to draw the same over the instep and about the ankle tightly enough to exclude snow, dirt, and moisture, and give a very neat and trim appearance, and also assisting the parts in retaining themselves in their folded position by the elimination of direct strains tending to open the same. The strain, being in a substantially straight line between the points *f* and *g*, tends to hold the edge of the flap *A* straight and therefore closed.

The upper above described is held in its closed or folded position, as shown in Figs. 1, 2 and 4, or in its open position, shown in Fig. 3, by means of a clasp or clasps comprising circumferentially disposed curved arms 16 and 17 secured to the upper by being inserted between the body and the lining thereof, said arms being hinged together at their rear ends by a hinge pin 18 and extending at their forward ends to points adjacent the folds *d* and *e*, respectively. Said forward ends of the arms 16 and 17 overlap, when the clasp

is closed as shown in full lines in Fig. 5, in substantially the same manner as the folds of the upper when the latter is in the closed position shown in Fig. 4, so that the 5 closing of the clasp results in a folding of the upper in the desired manner. One or more clasps composed of arms 16 and 17 are included in the upper at suitable points to hold the latter in place. Thus, in Fig. 1, 10 one is shown at the top of the upper, while in Figs. 2 and 3, in which is shown an upper slightly higher than that shown in Fig. 1, an additional clasp is provided between the top and the ankle. Each of said clasps 15 is so constructed as to cause the arms 16 and 17 to be yieldingly held in either the closed position shown in Figs. 1, 2, 4, and 7, and in full lines in Fig. 5, to hold the upper folded, or in the extended position shown in 20 Figs. 3 and 6, and in dotted lines in Fig. 5, to hold the upper in a distended position to permit the overshoe to be put on or taken off. To this end, in the particular construction shown, one of the arms of each clasp, 25 herein the arm 16, is formed adjacent the hinge pin 18 with a projection 19 cooperating with a spring 20 secured to the other arm 17 and having a rib 21 adapted to engage the projection 19 at either side. Thus, 30 when the arms 16 and 17 are swung outwardly, as shown in Figures 3 and 6 and in dotted lines in Figure 5, the projection 19 is engaged at one side of the rib 21 thereby yieldingly holding the arms in this position. 35 When said arms are swung inwardly the projection 19 rides over the rib 21, forcing the spring 20 back, and snaps to the other side thereof, thereby yieldingly holding the arms in closed position, as shown in Figure 40 7 and in full lines in Figure 5. The opposite sides of the rib 21 are preferably inclined so as to operate with a cam action upon the projection 19 to force the arms 16 and 17 either open or closed when moved 45 past the dead center position in one direction or the other.

In order to put the overshoe on, the upper is suitably grasped to swing apart the arms 16 and 17 of the two-position clasp and 50 open the upper, which is automatically held in this position until the foot has been inserted, after which the sides are merely pushed together, causing the clasp to close the upper and hold the same in closed position 55 against the leg of the wearer with any desired degree of pressure by the action of the spring 20 through the inclined face of the rib 21 against the projection 19. It will be seen that after the upper is closed, the 60 hand may be readily inserted from the top between the parts *a* and *b* and between the parts *a* and *c* to smooth down wrinkles and cause the parts to lie flat, the clasp yielding if necessary, but closing when the hand is 65 removed.

If desired the upper may be so arranged and folded as to form, when closed, two overlapping two-ply triangular flaps in place of the single flap A shown in Figures 1 and 2. Thus, in the construction shown 70 in Figures 8 to 10, the portion *b'* is folded over instead of under the tongue portion *a'*, being itself folded along the diagonal line *d'* to form a triangular flap *A'*, and the portion *c'* then folded along the diagonal line *e'* and over the portion *b'* to form a second triangular flap *A''*. The two lines of fold *d'* and *e'*, each of which extends diagonally from one side of the foot at the bottom to the opposite side of the leg at the top, cross one another over the instep, so that when the upper is drawn tightly about the leg of the wearer at the top, these parts will be drawn equally tightly over the instep and about the ankle in substantially 85 the same manner as the fold *e* of the single flap A shown in Figures 1 and 2. It will be understood that a two-position spring clasp substantially similar to the clasp above described will be employed in connection with the form shown in Figures 8 to 10, and that the free ends of the arms 16 and 17 of said clasp will be extended substantially to the folds *d'* and *e'*, respectively, so as to overlap when the upper is 95 folded.

In the form of the invention last described, the fold *e'* of the outer flap *A''* extends diagonally from the inner side of the foot to the outer side of the leg, as is also 100 preferably the case with the fold *e* of the flap A shown in Figures 1 and 2, so that the inner sides of both uppers are smooth, and danger of catching the exterior folds upon one another when walking is eliminated.

The overshoe above described in several alternative forms is not only neater in appearance than those usually in use, due to the absence of the usual outside fastening devices, but may be put on or taken off with far less time and trouble than any similar device heretofore used in which the upper is closed tightly enough to exclude snow, dirt and moisture. Said overshoe may be 110 instantly opened merely by grasping the opposite sides and pulling them apart, will maintain itself in open or distended position so as to facilitate the introduction of the foot thereinto, and may be as instantly 115 closed merely by wiping the opposite sides with the hands, or with one hand and the other foot, without the use of the fingers, the clasps springing into closed position and, by their overlapping ends, folding the upper in the proper manner and holding it 125 so folded. The usual separate outside fasteners are thus entirely eliminated, so that the labor and loss of time required for fastening and releasing the same are avoided, 130

while the overshoe presents an exterior surface having no projections which will catch the other clothing of the wearer.

Having thus described my invention, I 5 claim:

1. An article of footwear having a circumferentially closed upper which is folded upon itself along a diagonal line extending from a point near the bottom of the shoe 10 diagonally across to the opposite side of the leg at the top.
2. An article of footwear including a circumferentially closed upper having an exterior fold along a line extending over the 15 instep from a point near the bottom of the shoe at the inner side thereof diagonally across to the outer side of the leg at the top.
3. An article of footwear including a circumferentially closed upper having an exterior fold along a line extending over the 20 instep from a point near the bottom of the shoe at the inner side of the foot diagonally across to the outer side of the leg at the top, and a circumferentially disposed hinged 25 clasp for holding said upper in folded condition.
4. An article of footwear having an upper and a two-position circumferentially

disposed spring clasp associated therewith and adapted to hold the same in either a 30 distended or a closed position, said clasp comprising hinged arms having their free ends overlapping when said clasp is closed.

5. An article of footwear having a circumferentially closed upper which is folded 35 upon itself twice, and a two-position spring clasp associated with said upper and adapted to hold the same in a distended position or in a folded position about the leg of the wearer, said clasp having portions engaging 40 said upper adjacent the respective folds and overlapping one another to correspond to the overlapping of said folds.

6. An article of footwear having a circumferentially closed upper which is folded 45 upon itself along a line extending from a point near the bottom of the shoe on one side of the foot diagonally across to the opposite side of the leg at the top, and a two-position spring clasp associated with said 50 upper and adapted to hold the same in a distended position or in said folded position.

In testimony whereof I affix my signature.

GEORGE P. DIKE.
